UNITED STATES PATENT OFFICE.

HENRY W. WENDT, OF BUFFALO, NEW YORK, ASSIGNOR TO BUFFALO FORGE COMPANY,
OF BUFFALO, NEW YORK.

FORGE.

1,190,693.

Specification of Letters Patent. Patented July 11, 1916.

Application filed July 24, 1915. Serial No. 41,682.

To all whom it may concern:

Be it known that I, HENRY W. WENDT, a citizen of the United States, residing at Buffalo, in the county of Erie and State of New York, have invented a new and useful Improvement in Forges, of which the following is a specification.

This invention relates to blacksmiths' forges, more particularly of the portable type, which are adapted for use on railroads, bridges, structural steel works and elsewhere, necessitating transportation of the forge from place to place. The invention is not, however, necessarily restricted in application 15 to this type of forge.

The objects of the invention are to so mount the blower on the forge that it can be quickly and easily reversed and shifted from one to the other side of the hearth in position 20 to be readily operated either by a right-handed or left handed man standing at one or the other side of the forge; also to removably mount the blower and the twyer pipe so that they can be readily disconnected 25 from the hearth to facilitate the packing and transportation of the forge and in such a manner that the blower is rigidly and securely supported by the twyer pipe without the necessity for a separate supporting arm 30 or bracket.

In the accompanying drawings, consisting of two sheets Figure 1 is a side elevation of a forge embodying the invention. Fig. 2 is a fragmentary sectional elevation of the 35 hearth and twyer pipe on line 2—2, Fig. 4. Fig. 3 is a plan view of the twyer pipe and the supporting flange therefor, partly in section in line 3—3, Fig. 2. Fig. 4 is a plan view of the forge with the hood removed, 40 showing the blower in position at one side of the hearth to be operated by the left hand. Fig. 5 is a similar view, showing the blower reversed and in position at the other side of the hearth to be operated by the right hand.

45 A represents the hearth or pan and B, the hood of a forge, which, with the exception of the mounting of the blower and twyer pipe thereon, may be of any usual or suitable construction. In the forge shown, the 50 hearth is supported by upright legs a at the corners thereof and is provided with the usual depressed fire pot C with which the twyer pipe connects.

E represents a twyer connected with the 55 fire pot and F a twyer pipe or blast pipe

which extends from the twyer outwardly beneath the hearth and is provided with an outer end portion which preferably extends upwardly at an angle of about forty-five degrees, and on which the blower is mounted 60 and supported. The twyer and twyer pipe are preferably cast in a single piece which is removably secured in position and constitutes the sole support for the blower. The twyer is removably and rotatably connected 65 to the lower end of the fire pot C by suitable means, such for example, as a segmental circular plate g, which is bolted to the lower end of the fire pot and has a flange that projects under an outwardly projecting rim 70 flange g' on the twyer. The outer end of the twyer pipe is supported as by a bolt or securing device H, which extends through the pipe and through a segmental slotted plate h, which is suitably secured on the hearth 75 and the slot h' of which is curved concentrically with the center of the twyer. The bolt H is provided with a hand nut h², by means of which the pipe can be rigidly clamped to the slotted supporting plate h. 80 The twyer is adapted to be turned to different angular positions on its connection with the fire pot so that by loosening the securing bolt or device H, the pipe can be swung about the axis of the twyer as a center from a position in which its outer end 85 extends adjacent to one side of the hearth, as shown in Fig. 4, to a position in which its outer end extends adjacent to the opposite side of the hearth, as indicated in Fig. 5. 90 The pipe can be rigidly secured in either of these positions, or in any desired intermediate position by tightening the nut h². Any other suitable way of mounting and securing the twyer and blast pipe so that the pipe can 95 be swung from one to the other side of the hearth and secured may be employed.

The blower which is shown at I, may be of any suitable construction adapting it to be reversed on the outer end of the twyer 100 pipe so as to locate its operating crank handle at one or the other side of the blower. The blower shown is provided at one side thereof with an operating crank handle i, secured to a shaft located substantially mid-way between the front and rear edges of the blower casing, and the blower casing connects with the twyer pipe F by a discharge connection k, which extends radially from the casing mid-way between the opposite 105 110

edges thereof, and is detachably and reversibly connected to the end of the twyer pipe. By reason of this arrangement, the blower can be secured on the twyer pipe with its 5 operating handle located at either the right or the left hand side of the blower, and the handle will occupy corresponding positions relative to the hearth at opposite sides of the blower, and will be the same distance 10 from the hearth so that it can be operated with equal facility in both positions. The blower can be detachably secured to the outer end of the twyer pipe, so as to permit it to be readily disconnected and reversed by 15 any suitable means, as for example, by providing the discharge connection h of the blower with a dovetail or flanged end l , which fits in a co-operating dovetail or flanged clamp l' , on the upper end of the 20 twyer pipe having a movable jaw or member adapted to be moved to clamp and release the blower by a nut l^2 and bolt l^3 . The nut l^2 can be, if so desired, provided with a handle for turning the same so as to avoid 25 the necessity for a wrench or other tool.

In forges having a small or round hearth it is not necessary for the pipe to swing to the side, as the blower can be reversed on the twyer pipe to locate its handle at one or 30 the other side of the blower, and the handle conveniently operated with the pipe in a position centrally between the sides of the hearth, but when the invention is used in connection with forges having a rectangular 35 or large hearth, the twyer pipe is preferably mounted to swing from side to side of the hearth as explained, so as to place the blower near either side of the hearth where it can be more easily reached.

40 4. I claim as my invention:

1. In a forge, the combination with a hearth, of a blower, and an air pipe which connects the blower to the hearth and is arranged to move laterally to different positions relative to the hearth for placing the blower at one or the other side of the hearth, said blower being reversibly connected to 45 said pipe.

2. In a forge, the combination with a 50 hearth, of a twyer pipe pivotally connected to the hearth to swing laterally relative thereto, and a blower reversibly connected to the outer end of said pipe.

3. In a forge, the combination with a 55 hearth, of a twyer pipe pivotally connected

to the hearth to swing laterally relative thereto, means for securing said pipe in different positions, and a blower reversely connected to the outer end of said pipe.

4. In a forge, the combination with a 60 hearth, of a twyer pipe pivotally connected at its inner end to the hearth to adapt the outer end of the pipe to swing to different positions relative to the hearth, and a blower reversibly connected to the outer end of said 65 pipe and supported thereby.

5. In a forge, the combination with a 70 hearth, of a twyer, pivotally connected to the hearth, a twyer pipe connected to said twyer means for securing said pipe in different positions, and a blower secured to and supported by the outer end of said pipe.

6. In a forge, the combination with a 75 hearth, of a twyer pipe pivotally connected at its inner end to the hearth, a blower connected to and supported by the outer end of said twyer pipe, said twyer pipe being adapted to swing laterally to place the blower in different operative positions relative to the hearth, and means for securing 80 the twyer pipe with the blower in one or another of its operative positions.

7. In a forge, the combination with a 85 hearth, of a twyer pipe connecting with said hearth and extending outwardly beyond the same, and a blower having a casing provided with a discharge connection which is secured to the outer end of said twyer pipe by a connection adapting the blower to be reversed about the axial line of the outer end of said 90 twyer pipe for locating the operating handle of the blower at either side of the blower.

8. In a forge, the combination with a 95 hearth, of a twyer pipe connecting with said hearth and extending outwardly therefrom at an upward inclination and a blower having a casing provided with a discharge connection which extends therefrom substantially radially at the same inclination as the twyer pipe and is secured to said twyer pipe 100 by a connection adapting the blower to be reversed about the axial line of the outer end of pipe for locating the operating handle of the blower at either side of the blower.

Witness my hand this 22nd day of July, 105
1915.

HENRY W. WENDT.
